J. MURRIE & W. OTT.
TOOL FOR TURNING AND TRUING CRANK PINS.
APPLICATION FILED APR. 26, 1917.

1,235,914.

Patented Aug. 7, 1917.

UNITED STATES PATENT OFFICE.

JOHN MURRIE AND WILLIBALD OTT, OF LA CROSSE, WISCONSIN.

TOOL FOR TURNING AND TRUING CRANK-PINS.

1,235,914.

Specification of Letters Patent.

Patented Aug. 7, 1917.

Application filed April 26, 1917. Serial No. 164,692.

To all whom it may concern:

Be it known that we, JOHN MURRIE and WILLIBALD OTT, citizens of the United States, residing at La Crosse, in the county 5 of La Crosse and State of Wisconsin, have invented certain new and useful Improvements in Tools for Turning and Truing Crank-Pins, of which the following is a specification.

10 Our invention relates to hand tools for turning crank pins for the purpose of truing them.

The objects of the invention are to provide a strong and efficient tool for turning 15 and truing the pins of crank axles, and the like, which is capable of ready separation to enable it to be applied to the crank pins; to provide a yielding jaw opposed to the rigid cutter-carrying jaw and to provide a frame

20 for the jaws composed of parallel bars extended at their opposite ends to form the operating handles.

These objects we attain by the construction illustrated in the accompanying drawing, in which:

Figure 1 is a side elevation of our improved turning and truing tool.

Fig. 2 is a cross section on line 2—2, Fig. 1.

30 Fig. 3 is an end view.

A A' designate two parallel bars spaced apart and formed with oppositely projecting handles a a'.

B designates the fixed jaw formed of a 35 rectangular block having two opposite sides provided with longitudinal grooves b b receiving adjacent faces of the bars A A', which bars are secured to the said fixed jaw by transverse screws b'. A second fixed 40 block C is similarly secured between the bars A A' by screws b'. A rigid, easily separable rectangular frame or tool stock is thus formed within which slides the movable jaw B', provided with grooves b² b³, receiving 45 the bars A A' and permitting sliding movement thereon. The movable jaw B' is pressed toward the fixed jaw B by a plate spring E, the ends of which are notched to fit over the bars A A'. The tension of the 50 spring E is regulated by a screw e extending through the block C.

The adjacent faces of the jaws B B' are provided with V-shaped centering recesses b⁵ b⁶ for the pin to be turned and trued and 55 the opposite face of the movable jaw B' is provided with a smaller V-shaped recess and

so the centering of different sized crank pins is provided for by merely reversing the position of the movable jaw B'.

The fixed jaw B is provided with a radial 60 cutter-slot b⁸ which opens into the V-shaped groove b⁵ just a little to one side of its angle so that the edge d of the cutter D will work on the crank pin to be trued directly in the center line a⁵ between the two jaws. The 65 cutter D is adjusted by parallel screws d d passing through the fixed jaw B and bearing on the rear end of said cutter. The cutter is clamped in its adjusted position by a transverse set-screw d' extending through 70 bar A into engagement with the side of the cutter. Oil holes a⁹ extend through the fixed jaw to points near the edge of cutter D to supply same with oil at the cutting point. 75

To apply the tool to a crank pin simply remove the screws b² and withdraw the block or cross piece C, spring E and sliding jaw B. Then place the frame or stock over the crank pin, replace the jaw B', spring E, 80 block or cross piece C and screws b². By now adjusting the cutter D and the tension of spring E the tool may be rotated around the crank pin until it has become properly trued. The crank shaft to be operated upon 85 will be held rigidly by any suitable holder, such as a vise.

Where a cutter is fed direct to the surface of a crank pin held between two fixed jaws of a tool it is necessary to make the full 90 cut of the feed in a single revolution of the tool, which requires great exertion, depending upon the extent of the feed, but in our tool having the spring-pressed jaw a heavier feed may be made and the entire cut will 95 be taken with possibly a half dozen revolutions, and this results in much better work.

The tool may be made in different sizes and various changes may be made without departing from the scope of our invention. 100

What we claim is:

1. A tool for turning and truing crank pins comprising parallel oppositely extending handle bars, inner and outer rectangular jaws mounted between said handle bars and 105 having registering work centering recesses in their adjacent faces, the inner jaw being adjustable with respect to the outer jaw, a cutter mounted in the fixed jaw, a removable crossbar between the handle bars beyond the 110 adjustable jaw, screws extending through the handle bars into the ends of said cross-

- bar, and a set-screw extending through the crossbar for adjusting the inner adjustable jaw.
2. A tool for turning and truing crank pins comprising a pair of parallel oppositely extending handle bars, a fixed rectangular cutter-carrying jaw having grooved ends receiving the adjacent sides of said handle bars and secured thereto, a similarly grooved adjustable jaw slideable along said handle bars; the adjacent faces of the jaws having work receiving and centering recesses, a fixed crossbar beyond the adjustable jaw, screws or bolts passed through the ends of the handle bars into the ends of said crossbar to secure it removably in place, and a set-screw for the adjustable jaw mounted in said crossbar.
3. A tool for turning and truing crank pins comprising handle bars, fixed and movable work centering jaws, a cutting tool carried by the fixed jaw, and an adjustable tension spring pressing the movable jaw toward the fixed jaw.
4. A tool for turning and truing crank pins comprising oppositely extending parallel handle bars, a fixed jaw mounted between said bars and having a cutting tool, a sliding jaw between said handle bars; said jaws having work receiving recesses in their adjacent faces, a fixed crossbar secured removably between the handle bars beyond the sliding jaw, a tension spring engaging the outer end of the sliding jaw, and a set-screw extending through the said crossbar into engagement with said spring.
5. A tool for turning and truing crank pins comprising handle bars, a fixed tool-carrying jaw between said handle bars and having a work-receiving recess, a sliding reversible jaw having different sized work-receiving recesses to register with the recess in the fixed jaw, a removable crossbar secured between the handle bars beyond said sliding jaw, a set-screw extending through said crossbar, and a bowed spring between the inner end of said set-screw and the sliding jaw.
6. A tool for turning and truing crank pins comprising handle bars, a fixed jaw mounted between the handle bars and having a work-centering recess, a cutting tool mounted in the said jaw with its cutting edge on a line intersecting the center of the work-receiving recess, a sliding jaw having a work-centering recess registering with that of the fixed jaw, a spring pressing said jaw toward the fixed jaw, and a removable crossbar beyond the sliding jaw and having a screw engaging said spring.
7. A tool for truing crank shafts comprising a separable frame or stock having fixed and sliding jaws provided with registering work-receiving recesses, a cutting tool mounted in the fixed jaw, and a tension spring pressing the sliding jaw toward the fixed jaw.

In testimony whereof we affix our signatures.

JOHN MURRIE.
WILLIBALD OTT.
